(57) **CLAIM**

The ornamental design for a cooking container, as shown and described.

DESCRIPTION

FIG. 1 is a front, left-side, top perspective view of the cooking container;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and

FIG. 7 is a bottom plan view thereof.

FIG. 8 is an enlarged front, left-side, top perspective view of the top part of the cooking container without the bottom part;

FIG. 9 is a left-side elevational view thereof;

FIG. 10 is a right-side elevational view thereof;

FIG. 11 is a rear elevational view thereof;

FIG. 12 is a front elevational view thereof;

FIG. 13 is a top plan view thereof; and

FIG. 14 is a bottom plan view thereof.

FIG. 15 is an enlarged front, left-side, top perspective view of the bottom part of the cooking container without the top part;

FIG. 16 is a front elevational view thereof;

FIG. 17 is a rear elevational view thereof;

FIG. 18 is a right-side elevational view thereof;

FIG. 19 is a left-side elevational view thereof;

FIG. 20 is a top plan view thereof; and,

FIG. 21 is a bottom plan view thereof.

The broken lines depict parts of the cooking container that form no part of the claimed design.

1 Claim, 21 Drawing Sheets
